ULTRASONIC CLEANING APPARATUS

Carl R. Yurdin, Port Washington, N.Y., assignor to Branson Instruments, Incorporated, Stamford, Conn., a corporation of Delaware

Filed July 26, 1968, Ser. No. 12,907

Term of patent 14 years

Int. Cl. D15—06

U.S. Cl. D49—1

FIG. 1

FIG. 2

FIG. 3

FIG. 4

FIG. 5

FIGURE 1 is a front and top perspective view of my design depicting the ultrasonic cleaning apparatus;

FIGURE 2 is a top plan view;

FIGURE 3 is a front elevational and a rear elevational view;

FIGURE 4 is a left side and right side elevational view, and

FIGURE 5 is a bottom plan view.

The dominant features of my design reside in the full line portions shown.

I claim:

The ornamental design for an ultrasonic cleaning apparatus, substantially as shown and described.
